UNITED STATES PATENT OFFICE.

PHILLIPP F. FLAGGE, OF DUBUQUE, IOWA, ASSIGNOR TO KLAUER MANUFACTURING CO., OF DUBUQUE, IOWA.

BUILDING STRUCTURE.

Application filed January 16, 1923. Serial No. 612,979.

This invention relates to building structures and is particularly directed to a water-tight joint.

Objects of this invention are to provide a joint for metallic paneling, especially for roofing or for building structures, which joins successive panels in a water-tight manner, which acts as a reinforce, and which avoids the use of nails or other similar fasteners.

Further objects are to provide a joint for metal panel which will conduct away any water that might by any chance get into the seam acting, in this respect, like a gutter; which, although adapted for any type of metal paneling, is particularly adapted for roofing and for use where a slight motion between parts is required as in car roofing where slight twisting or distorting movements occur; and to provide a joint which may be easily formed.

Further objects are to provide a metal panel roof which is adequately reinforced throughout its extent, which is secured at both ends of each of the panels, and which may be rapidly and easily assembled.

Embodiments of the invention are shown in the accompanying drawing, in which:—

Figure 1 is a fragmentary perspective view of a building embodying the invention.

Figure 2 is a detail of the ridge pole and the associated portions of the roofing.

Figure 3 is a detail of the lower end or edge of the roofing.

Figure 4 is a transverse sectional view thru one of the tubular connecting members and the associated portions of the paneling.

Figure 5 is a view similar to Figure 4 showing a different form of tubular connecting member.

Although this invention is applicable to various types of building structures and roofing, it has been shown as applied to a garage or similar building, as illustrated in Figure 1, and referring more particularly to said figure it will be seen that the roofing is composed of a plurality of sheet metal panels 1 joined by means of tubular members 9.

The walls are similarly formed of a plurality of sheet metal panels 3 joined by tubular members 4. The upper portion or ridge of the roof is provided with an angle-iron ridge pole 5, upon which the panels 1 rest. It is to be noted that the upper ends of the

panels overlap the upper edge of the ridge pole, as indicated at 6.

The side panels and the roofing panels are joined in the same manner, and it will be necessary, therefore, to describe only one. As may be seen from Figure 4, the panels 1 are provided with reentrant marginal portions 7 which are upwardly turned and are converging. These marginal portions are equipped with inturned lips 8 which parallel such portions and are located above and slightly spaced therefrom. The tubular connecting member 9 has interiorly arranged lips 10 which converge and are fitted between the lips 8 and the marginal portions 7. In this manner a water tight and reinforced joint is formed between the panels 1. Water which may, for any reason, get into the tubular member will flow downwardly therethru, as the upturned lips 10 form, in effect, a double gutter, or a gutter 75 on each side of the space between adjacent panels. The interior of the gutter is smooth and unobstructed.

A further form of tubular connecting member is illustrated in Figure 5. This member is provided with upwardly converging walls 11 and with inwardly directed portions 12 which terminate in angularly arranged lips 13, the member being in effect triangular in cross section. The panels 1 in this case are provided with juxtaposed marginal portions 14 equipped with inturned lips 15, receiving between them, the lips 13.

In order to securely hold the roofing in position, a clamp consisting of a casting 16 is provided for each pair of opposed tubular members 9, as may be seen from Figure 2. This clamp has arms 17 which are located within the tubular members and are adapted to clamp such members and the adjacent portions of the paneling 1 against the angle-iron 5. A bolt 18 equipped with a nut 19 and a bearing plate 20 is used to cause the clamp to bind the members in position, as will be readily understood.

The side panels 3 are joined by tubular members 4 which may be identical in formation and operation to the tubular members 9. These side panels are extended outwardly beneath the eaves of the roof, as indicated at 21, and are provided with inturned lips 22. The lower end of the tubular members

9 are provided with a hollow horn shaped plug 23 which may conveniently be formed of sheet metal. This plug has its projecting portion gradually flattened, as indicated at 5 24, and terminates in hooks 25 which are received between the lips 22 and the adjacent portion 21 of the side members 3.

Any suitable form of ridge cap, as indicated at 26, may be employed, and may be 10 suitably apertured to receive the tubes 9, as indicated in Figures 1 and 2.

It is to be noted that the paneling and the connecting tubular members are imperforate and do not require fasteners of any kind to 15 retain them in position. It is also to be noted that the tubular members, the outer end retaining means, and the paneling are all formed from sheet metal.

The angle-iron ridge pole 5 gives a material degree of stiffness and rigidity to the 20 roof and the tubular members vastly increase the stiffness and strength of the roof, thus serving both as interlocking connectors and as reinforces.

If desired, the tubular members may be 25 made of heavier stock than the paneling, as shown in Figure 4. The stiffness and strength of the tubular members is thus materially increased and they may more 30 readily serve as the sole supporting means for the roofing between the ridge pole and the eaves.

This type of roof is adapted to widely

varying uses, such, for instance, as that 35 described in detail in this application, and also for roofing for cars. It is to be noted that when used as a roofing for cars, the slight twisting motion or relative movements occurring in different portions of the roof are 40 easily cared for by this construction without subjecting any portions of it to destructive strains.

Although the invention has been described in considerable detail in the specific case 45 illustrated, it is to be understood that the invention is not to be limited except as defined in the appended claim.

I claim:

A metallic building structure comprising 50 a tubular connecting member having longitudinal inclined reentrant lips forming a double gutter, and a plurality of flat panels having their marginal portions bent to engage both faces of said lips to be retained in position thereby while permitting slight longitudinal movement between said panels and said connecting member, said connecting member being of heavier material than said panels and being of sufficient beam strength to serve as the sole supporting means for 55 said panels.

In testimony that I claim the foregoing I have hereunto set my hand at Milwaukee, in the county of Milwaukee and State of Wisconsin.

PHILLIPP F. FLAGGE.
